RETRACTABLE PINTLE RIG FOR LAYING
SHEET METAL FLOORING

Leo C. Luke, Evansville, Ind., assignor to International Steel Company, Evansville, Ind., a corporation of Indiana

Application December 31, 1948, Serial No. 68,695

5 Claims. (CL 294—93)

1

My invention relates broadly to transportation equipment, and more particularly to the construction of an improved rig for laying a sanitary floor on the base structure of a transportation unit.

One of the objects of my invention is to provide an improved construction of rig for laying metallic sheet flooring on a base structure.

Another object of my invention is to provide an arrangement of retractile pintle rig for engaging and supporting a metallic sheet flooring for suspending and placing the metallic flooring sheet within the confines of a base structure for automatic release when the flooring is properly located with respect to the base structure.

Another object of my invention is to provide an arrangement of rig for suspending a metallic floor of relatively large area on projectable pintles operative to introduce the flooring into the confined area of a base structure for movement from an elevated position to a position over the base structure for automatic release when the metallic flooring reaches a position of rest on the bottom of the base structure.

Other and further objects of my invention reside in an arrangement of slidable pintles for a floor suspension and installation rig as set forth more fully in the specification hereinafter following by reference to the accompanying drawings in which:

Figure 1 schematically illustrates a section of metallic flooring being lowered into a base structure by the rig of my invention prior to contacting the bottom of the base structure; Fig. 2 illustrates the rig of Fig. 1 after the sheet flooring suspended thereby has reached a position contacting with the bottom of the base structure; Fig. 3 is a plan view showing the rig just after release of the metallic flooring with respect to the base structure; Fig. 4 is an enlarged view partially broken away and shown in section and illustrating the suspension rig, the pintles therein and the metallic sheet flooring engaged thereby during the suspension and lowering process illustrated in Fig. 1; Fig. 5 is a view similar to that of Fig. 4 but illustrating the position of the sliding pintles just after the release of the metallic flooring and installation thereof on the bottom of the base structure; Fig. 6 is a view similar to Fig. 5 except showing the fragmentary end of the rig where the rig is illustrated as lowered still further into the base structure with the metallic flooring released therefrom; Fig. 7 is a side elevational view of the projecting end of one of the pintles; Fig. 8 is a vertical sectional

2

view taken on line 8—8 of Fig. 7; and Fig. 9 is a vertical sectional view taken on line 9—9 of Fig. 4.

My invention is directed to a rapid method of and apparatus for assembling a sheet flooring with respect to a base structure for producing a sanitary surface which may be readily washed and cleaned. The invention is particularly directed to a construction of retractile and projectable pintle rig for suspending metallic sheet flooring and moving the flooring into position with respect to the base structure where it may be released for installation on the bottom of the base structure. I have found the rig of my invention very practical for laying stainless steel flooring in refrigerator cars where a mass of very substantial weight of the order of 500-600 lbs. is lowered into position and released at the bottom for installation. The rig is provided with 20 a multiplicity of laterally extending frame members in the opposite ends of which slidable pintle members are provided. The slidable pintle members engage in apertures along the side walls of the metallic sheet constituting the floor, enabling 25 the metallic sheet to be suspended in a catenary, dimensioned to fit a confined space such as the enclosure of a transportation unit such as a trunk or refrigerator car with the pintles in wholly retracted position. As the catenary formed by the sheet flooring flattens out against 30 the bottom of the base structure, the slidable pintles move outwardly with respect to the frame members and automatically release the suspended flooring, allowing the flooring to settle into position for installation on the base structure.

Referring to the drawings in more detail, reference character 1 schematically designates a transportation unit such as a refrigerator car having a bottom 2 and opposite side walls 3 and 4. A normally extending frame structure 5 is provided and suspended through suitable suspension means 6 from a crane adapted to raise and lower the frame structure with respect to the enclosure constituting the transportation unit. The frame structure is connected through 45 suspension members 7 and 8, and 9 and 10, with horizontally extending angle members 11 and 12, and 14 and 15, respectively. The angle members 11 and 12 extend in spaced longitudinal positions and support the coplanar frame members 16, 17, and 18, 19, respectively. The frame members 16, 17, and 18, 19, form with the longitudinal extending angle members 11, 12 and 14, 15, a pair of polygonally-shaped, horizontally extending 50 ing pendent frame structures suspended from

3

each end of frame structure 5. These polygonally-shaped frame structures are dimensioned so that the linear dimension of frame members 16, 17 and 18, 19 is appreciably less than the interior lateral dimension of the enclosure of the transportation unit. The maximum longitudinal dimension of both of the pendent frame structures is also appreciably less than the longitudinal dimension of the transportation unit 1.

In the arrangement shown the maximum longitudinal dimension of the frame structure, from transversely extending frame member 16 to transversely extending frame member 19, is appreciably less than one-half the length of the transportation unit. The reason for this relative proportioning of the pendent frame structures with respect to the interior dimensions of the transportation unit is to permit the introduction of the sheet-like metallic flooring, represented generally at 20, through the open top of the transportation unit.

The metallic sheet flooring 20 is formed from stainless steel or plastic sheet or other material which may be produced either in a continuous sheet or assembled from laterally extending strips, as represented in Fig. 3. Where the flooring is assembled from laterally extending strips a plurality of strips are welded at their adjoining lateral edges, as represented at 20a, 20b, 20d and 20e, to form a flat continuous sheet of flooring which may be readily washed and cleaned. The connecting strips each have upwardly extending side walls 20' and 20''. These side walls are preformed on a metal bending machine so that they extend substantially normal to the plane of the strip 20. Corresponding side walls 20' and 20'' are formed on each of the strips constituting the entire area of metal flooring. The end strip of the metallic flooring represented at 20''' extends under the end partition 21 in the transportation unit 1 which separates the storage space from the closure 22 at the end of the transportation unit which houses the refrigeration unit.

The upwardly extending side walls 20' and 20'' provided on each of the laterally extending strips making up the flooring are each welded to the other as represented in Fig. 3, so that a trough-like sheet is provided. The side walls of the trough-like sheet indicated at 20' and 20'' are provided with prearranged sets of transversely aligned apertures which I have represented in Fig. 3 at 23—24, 25—26, 27—28 and 29—30. These apertures are in transversely aligned pairs in alignment with the horizontally extending frame members indicated at 16, 17, and 18, 19. The horizontally extending frame members have tubular portions at each of the ends thereof which I have represented more clearly in Figs. 4, 5 and 9, as for example at 16a. These tubular portions each receive a slidable pintle member which I have represented in Fig. 3, at 31, 32, 33, 34, 35, 36, 37 and 38. The pintle members are keyed in the opposite ends of the frame members so that they will slide therein to laterally project or retract without rotating.

In the form of my invention shown, I shape the tubular portions of the laterally extending frame members 16, 17 and 18, 19 so that they are polygonal in section and provide slidable pintles of corresponding cross section. Thus the pintles are free to project or retract without rotating in the frame members. Each of the slidable pintle members has a pin projecting from the end thereof which I have indicated at 40

4

and shown more clearly in Fig. 7. The pin 40 has a needle-like, streamlined, terminus adapted to enter and be retracted from the aligned aperture in the slide wall of the metallic flooring. Each pin 40 has a transverse slotted portion 41 therein adapted to engage the upper internal edge of the aperture in the side wall of the flooring as the pin is projected through the aperture.

As represented in Fig. 1, the metallic sheet flooring is initially proportioned in size to the base structure on which it is to be laid and has the side walls 20' and 20'' thereof engaged by the pins 40 of the oppositely arranged, slidable pintle members 31, 32. Upon engagement in this manner the sheet of metallic flooring may be picked up from a loading position by a crane with the entire area of metallic flooring gravitationally suspended and pendently hanging in a catenary, as represented in Fig. 1. Because of the proportioning of the linear dimensions of the coplanar frame members 16, 17 and 18, 19, the entire area of flooring may be lowered through the open top of the transportation unit, as represented in Fig. 1, with the metallic flooring hanging in a catenary as shown, and with the slidable pintle members all in retracted position as represented in Figs. 1 and 4. As the metallic flooring 20 is deposited on the base structure 2 of the transportation unit, as represented in Fig. 2, the catenary curve of the suspended metallic flooring flattens out. This results in the outward flexing of side walls 20' and 20'', resulting in the automatic projection of the slidable pintles 31, 32, 33, 34, 35, 36, 37 and 38 to a position in which the side walls 20' and 20'' flex outwardly to the position illustrated in Fig. 5, in which the side walls spring clear of the slots 41 in pins 40.

The rig, when further lowered, is entirely free of the metallic flooring 20 as represented in Fig. 6. In this position the side walls 20' and 20'' of metallic flooring 20 spring to a position adjacent the interior of the transportation unit as represented by the side walls 2 and 3 thereof in Fig. 6, and shown in plan view in Fig. 3. The rig may now be raised by the crane from the transportation unit with the sheet flooring laid in position for installation in sealing relation to the side walls of the transportation unit.

The material forming the sheet-like flooring 20 has substantial resiliency and the side walls 20' and 20'' are flexed in accordance with the position of the catenary of the weighted flooring 20. To insure this flexing the side walls 20' and 20'' are initially shaped in a bending machine so that they are vertically disposed in planes substantially normal to the horizontal plane of the sheet-like flooring 20. By gravitationally employing the mass of the sheet-like flooring 20 to flex the side walls 20' and 20'' the projection of the pintle members is controlled and the ultimate release of the apertured side walls from engagement with the slotted pins 40 effected.

While I have shown the rig of my invention applied to the laying of flooring in a refrigeration car, I wish it to be understood that this is to be considered in the illustrative sense and that the rig is equally applicable to the laying of flooring in all types of transportation units and is in no sense restricted to use in refrigeration cars.

I have found the method of laying sanitary floors in transportation units as set forth herein and the construction of the rig, as shown herein, 75 very effective, but I realize that modifications in

the details of my invention may be made and I desire that it be understood that no limitations upon my invention are intended other than may be imposed by the scope of the appended claims.

What I claim as new and desire to secure by Letters Patent of the United States is as follows:

1. A rig for laying sheet flooring comprising a horizontally extending frame structure, including a plurality of coplanar frame members each having linear dimensions appreciably less than the interior lateral and longitudinal dimensions of the base structure on which the sheet flooring is applied, said frame members terminating in laterally extending tubular portions, slideable pintle members carried in said tubular portions, said pintle members each having a slotted terminus thereon for engaging apertured edges of the side walls of a metallic sheet constituting the flooring for suspending said metallic sheet in a catenary adapted to be deposited on the base structure and automatically released as the catenary portion of said sheet contacts the base structure and said slideable pintle members are drawn outwardly to positions where the apertured edges of the side walls of the metallic sheet disengage from the slotted termini of said pintle members.

2. A rig for laying sheet flooring comprising a horizontally extending frame structure, including a multiplicity of coplanar frame members each having linear dimensions appreciably less than the interior lateral and longitudinal dimensions of the base structure on which the sheet flooring is applied, said frame members terminating in laterally extending tubular portions, each having a polygonal section, slideable pintle members of corresponding polygonal section slideable into and out of the ends of said frame members and each having a transversely slotted terminus to engage apertured edges of the side walls of a metallic sheet constituting the flooring for suspending said metallic sheet in a catenary adapted to be deposited on the base structure and automatically released as the catenary portion of said sheet is deposited on the base structure, and the side walls which are connected therewith oriented outwardly for drawing said slideable pintle members outwardly to positions to disengage the apertured edges of the side walls of said sheet from the slotted termini of said pintle members.

3. A rig for laying sheet flooring comprising a horizontally extending frame structure, including a plurality of spaced coplanar frame members each having linear dimensions appreciably less than the lateral and longitudinal dimensions of the base structure on which the sheet flooring is applied, said frame members terminating in laterally extending tubular portions, pintle members carried by said frame structure, said pintle members having a non-rotative but slideable connection with the lateral ends of said frame members, and each having a transversely slotted terminus to engage apertured edges of the side walls of a metallic sheet constituting the flooring for suspending said metallic sheet in a catenary adapted to be deposited on the base structure and

automatically released as the catenary portion of said sheet is deposited on the base structure, and the side walls which are connected therewith oriented outwardly for drawing said slideable pintle members outwardly to positions to disengage the apertured edges of the side walls of said sheet from the slotted termini of said pintle members.

4. A rig for laying sheet flooring comprising a horizontally extending frame structure, including a plurality of spaced coplanar frame members each having linear dimensions appreciably less than the lateral and longitudinal dimensions of the base structure on which the sheet flooring is applied, said frame members terminating in laterally extending transverse rectangular tubular sections, pintle members carried by said frame structure, said pintle members each having a rectangular transverse section slideable within the transverse rectangular tubular sections of said frame members, said pintle members each having a transversely slotted terminus to engage apertured edges of the side walls of a metallic sheet constituting the flooring for suspending said metallic sheet in a catenary adapted to be deposited on the base structure and automatically released as the catenary portion of said sheet is deposited on the base structure, and the side walls which are connected therewith oriented outwardly for drawing said slideable pintle members outwardly to positions to disengage the apertured edges of the side walls of said sheet from the slotted termini of said pintle members.

5. A rig for laying sheet flooring comprising a horizontally extending frame structure, including a plurality of spaced coplanar frame members each having linear dimensions appreciably less than the lateral and longitudinal dimensions of the base structure on which the sheet flooring is applied, said frame members terminating in laterally extending tubular portions, slideable pintle members carried in said tubular portions, said pintle members each having a pin projecting therefrom for engagement through apertures in the side walls of a metallic sheet constituting the flooring for suspending said metallic sheet in a catenary adapted to be deposited on the base structure and automatically detached from said pins as the catenary portion of said sheet is laid on the base structure and the side walls of said metallic sheet angularly moved upwardly and outwardly to a position drawing the slideable pintle members to a position for disengaging the apertured side walls of said flooring from said pins.
